UNITED STATES PATENT OFFICE.

CLARKE P. POND, OF PHILADELPHIA, PENNSYLVANIA.

MECHANICAL MOVEMENT.

1,279,903.

Specification of Letters Patent. Patented Sept. 24, 1918.

Application filed March 28, 1917. Serial No. 158,066.

To all whom it may concern:

Be it known that I, CLARKE P. POND, a citizen of the United States, residing in Philadelphia, Pennsylvania, have invented 5

Mechanical Movements, of which the following is a specification.

One object of my invention is to provide a novel combination of mechanical elements whereby a substantially constant operating 10 force applied to a driving member at a substantially uniform rate is caused to exert a force on a member to be operated which shall vary from a minimum to a maximum or vice versa, the invention more particularly 15

contemplating a device especially designed for swinging window sashes on their supporting hinges or pivots with a force which shall be automatically increased at a definite rate as said windows are moved in one direction 20 and correspondingly diminished as they are moved in the opposite direction.

A further object of the invention is to provide a relatively simple, substantial and efficient mechanical movement whereby rotary motion may be transformed to rectilinear movement, the arrangement of parts being such that power delivered to one of the elements of the device at a substantially uniform rate shall be transferred to a structure 25 to be operated at a variable rate.

More particularly it is desired to provide a combination of parts whereby the operation of a driving member at a constant speed shall result in operating a driven member 30 at a variable speed; the arrangement of parts being such as to suit the apparatus for the operation of certain types of sash in which the load gradually increases as the sash are opened and similarly decreases as

35 said sash are closed. My device is especially adapted to replace those forms of constant speed mechanism which since they required a gear reduction sufficient to permit easy operation of the driving motor or hand chain 40 at the maximum loads, necessarily also operated the sash or other member at slow speeds under conditions of minimum load.

These objects and other advantageous ends I secure as hereinafter set forth, reference 45 being had to the accompanying drawings, in which,

Fig. 1 is a side elevation illustrating the preferred form of my invention;

Figs. 2 and 3 are respectively a front

elevation and a plan of the apparatus shown 55 in Fig. 1; and

Fig. 4 is a side elevation of a modified form of the invention.

In the above drawings 1 represents a frame or other suitable form of supporting 60 structure constructed in the present instance for attachment to a vertical surface such as a wall, column or the like, and such frame includes two horizontally projecting members 2 and 3, spaced apart to provide bearings or guides 4 and 5 for a vertically extending screw in the form of an elongated threaded rod 6. The frame likewise has rigidly connected to or integral with it two substantially parallel vertically extending 65 channel members 7 spaced apart to provide guides for a pair of blocks 8, to which a head piece 9 on the upper end of the screw 6 is connected by a spindle or pivot pin 10. The two channel guides 7 are rigidly connected to the frame 1 as well as braced by means of a bracket structure 11, whereby 70 they are suitably reinforced against a force tending to deflect their upper ends toward the left from the position shown in Fig. 1. 80

Operative in the space between the frame projections 2 and 3 is a horizontally mounted chain wheel 12 whose hub is threaded to constitute a nut for the screw 6 and this wheel is engaged by a flexible operating member 85 in the form of an endless chain 13 whose main portion after passing around a pair of idler pulleys 14 and 15, extends vertically downward. These idlers are mounted on spindles journaled in suitable bearings provided by laterally and downwardly extending arms 16, suitably placed on the frame structure 1.

At suitable points, preferably immediately above the chain pulley 12, are mounted 95 a pair of sheaves or pulleys 17 and 18 operative in parallel vertical planes and mounted on spindles supported partly by the frame structure 1 and partly by bearing brackets 19 forming part of or rigidly connected to said structure. These two pulleys 17 and 18 have passing around them a pair of flexible power transmitting members in the form of chains 20 and 21, the upper runs of which are connected together by a 100 yoke 22, while their lower runs are similarly connected by a yoke 23.

The ends of two horizontally extending

parallel rods or cables 24 and 25 of any desired lengths are respectively connected with these two yokes 22 and 23, and their opposite ends may be connected by members 5 similar to the chains 20 and 21, passing around suitable supporting pulleys of the same construction as the pulleys 17 and 18, so that said rods or cables with the chains at their opposite ends, form in effect an endless power transmitting line whose two members 24 and 25 are simultaneously movable in opposite directions and have connected to them any desired members to be operated, such as a series of swinging or 10 other movably mounted window sashes, which for example, may be arranged as described and claimed in my Patent No. 886- 15 851, dated May 5, 1908. In the present case, however, as the mechanism has to do with 20 means for transmitting power from the chain 13 to the rods 24 and 25, I have not illustrated this apparatus for supporting and guiding the opposite ends of said rods, especially since a typical form of such apparatus is disclosed in my patent aforesaid 25 and forms no part of the present invention.

The yoke 22 and the upper end portion of the screw 6 provided by the head 9, are connected by a member in the form of a beam 26 which is illustrated as pivoted to 30 each of said elements and is preferably made to have a depth increasing from both of its end toward its middle. At or adjacent this latter point the beam or link 26 is 35 connected by a pair of links 27 to a point on the fixed frame 1 adjacent the pulley wheels 17 and 18, by means of a pivot pin whose center line is immediately adjacent or within a horizontal plane defined by the upper runs 40 of the chains 20 and 21. Both of the links 27, like the link or beam 26, are preferably of increased depth from the ends toward their middle parts.

With the above described arrangement if 45 power be applied by hand or machine to the chain 13 so as to turn the chain wheel 12 at a substantially constant rate in one direction, the screw 6 will be longitudinally moved through the nut constituting the hub of 50 said chain wheel, and if the parts be in the relative positions shown in full lines in Fig. 1, the rotation of said wheel 12 in the proper direction will move the head 9 of said screw downwardly in its guides 7. Owing to the 55 coaction of the members 26 and 27 and the rod 25, the lower runs of the chains 20 and 21 will be moved in the direction indicated by the arrow, Fig. 1. It will be noted that while at the start, this movement is relatively 60 rapid and the action of the member 26 is such that the force exerted by the rod 25 is a minimum, the rate of movement diminishes and the force exerted increases as the parts move into a position beyond the 65 positions indicated in dotted lines until by

the time the head 9 reaches the lower limit of its movement, the rod 25 is moving at a reduced rate while the force exerted upon it is a maximum.

Conversely if the direction of the operation of the chain 13 be reversed, the head 9 is moved upwardly in its guides, and while the force exerted to move the rod 24 in the direction of the arrow, Fig. 1, is a maximum, the speed of movement of said rod 75 and its attached apparatus is increased from a minimum until the parts approach the position shown in full lines, Fig. 1, when the speed of movement is a maximum and the force exerted is a minimum. 80

Such a combination of parts as that above described is particularly valuable for the operation of lines of window sashes such as are commonly employed in factories, power houses and the like, where the power required to move such sashes increases as these are swung out of a vertical position, but where nevertheless it is desirable to maintain the load on the operating motor substantially constant regardless of the position of said sashes. 90

As will be understood by those skilled in the art, there are available for use other devices whereby the head 9 and therefore the upper end of the beam 26, may be caused to move in the same manner as with the mechanism shown in Figs. 1 to 3 of the drawings. Among such devices may be noted the combination of parts shown in Fig. 4 wherein I have substituted a vertically extending rack 40 for the screw 6 and have provided a pinion 41 at all times in mesh with said rack. Since it is advisable that the various parts shall be at all times locked in any given position, I have provided means for locking this rack and at the same time actuating it, consisting of a worm wheel 42 fixed to the shaft 43 on which the pinion 41 is mounted and driven by a worm 44. As before the motive power for operating the apparatus may be provided by any suitable driving means such as the chain shown connected to the worm. 105

With such apparatus as that above described, it is conveniently possible to move 115 one or more groups or series of sashes in a forge shop, foundry or other factory where smoke or gases are developed at intervals, so as to quickly open them sufficiently for winter ventilation and similarly close such partial opening at several times the speed which would be possible with the ordinary forms of mechanism. 120

I claim:—

1. The combination of two members movably guided in straight lines at right angles to each other; a bar pivoted adjacent its ends to said members respectively; a relatively fixed structure; and a link pivotally connected to said fixed structure in a line 125 130

passing through the point of intersection of the lines of movement of said members and also pivotally connected to said bar.

2. The combination of two members movable in straight lines at right angles to each other; a fixed structure having a guideway for one of said members; a screw connected to said member; a nut on the screw; means for turning the nut to longitudinally move the screw and the member; a second member movable in a line at right angles to said first member; a bar connecting said members; and means connected to the bar for causing that part thereof connected to the second member to move in a straight line when the nut is turned.

3. The combination of a fixed structure; a member movable thereon in a straight line; a screw connected to said member; a pulley having a threaded hub for the passage of said screw; a flexible element for turning said pulley; a second member movable in a line at right angles to that of the first member; a bar connecting said members; and a link for causing that part of the bar connected to the second member to move in a straight line.

4. The combination of a fixed frame having an elongated guideway; a head slidable

in the guideway; a screw connected to the head; means for actuating the screw to move the head in the guideway; a power transmitting member extending adjacent the screw; a bar pivotally connected to the head and to said power transmitting member; with a link pivoted to the bar, and also pivoted to the frame in a line passing through both the power transmitting member and through the screw.

5. The combination of a supporting frame having an elongated guideway and a bearing; a head slideable in the guideway; a screw operative in the bearing and connected to the head; a nut on the screw held from longitudinal movement by the bearing; a pulley on the nut; a member for turning the pulley; an endless member to be actuated; a pulley on the frame partially supporting said endless member; a link pivoted at one end to the frame; with a bar having one end connected to the head, its second end connected to the endless member and its middle portion connected to the second end of the link.

In witness whereof I affix my signature.

CLARKE P. POND.
